UNITED STATES PATENT OFFICE.

OTTO RANGNOW, OF PHILADELPHIA, PENNSYLVANIA.

TRUNK-TRAY HOLDER.

No. 919,076.

Specification of Letters Patent.

Patented April 20, 1909.

Application filed August 3, 1907. Serial No. 386,924.

To all whom it may concern:

Be it known that I, OTTO RANGNOW, a citizen of the United States, residing at Philadelphia, in the county of Philadelphia and 5 State of Pennsylvania, have invented certain new and useful Improvements in Trunk-Tray Holders, of which the following is a specification.

My invention relates to improvements in a 10 trunk tray holder and particularly relates to a latch located in the lid of the trunk for holding the trunk tray in a raised position.

The object of my invention is to provide 15 a tray holder which will assume the proper position, when the lid is raised so as to receive and automatically engage the tray and hold it in a raised position.

A further object of my invention is to provide means for disengaging the latch from 20 the tray when the lid of the trunk is being let down so that the lid may be again raised without raising the tray.

Referring to the drawing:—Figure 1. is a 25 vertical cross section of a trunk showing my improved trunk tray holder embodied therein, and, Fig. 2. is a perspective view of the tray holder detached.

In the drawings 1 represents the body of 30 the trunk and 2 the lid of the trunk. The lid is pivoted to the body by the hinges 3 and is shown in a raised position in full lines and in a closed position in dotted lines.

The tray 4 is shown in full lines resting upon the body of the trunk, it being supported by the slip hinges 5 and the projecting plates 6 located at either end of the tray. When the tray is raised it swings on the hinges 5 and assumes the position shown in dotted lines.

40 The latch 8 is pivoted to a plate 9, which is secured to the inside of the end of the lid 2, of the trunk. Said latch 8 is provided with a projection 10 to form a hook to engage the projecting plate 6 on the tray. The end of 45 the said latch is curved so that the projecting plate 6, on the tray, will depress the end of the latch and automatically slide over the said projection 10. Said latch will then engage the plate 6 and hold the tray in a raised 50 position. The latch 8 is continued beyond the pivot and is provided with an enlarged portion to form a weight, so that the said latch will naturally assume the position shown in full lines when the lid 2 is raised, or 55 in the position shown in dotted lines, when the lid is closed.

The plate 9 is provided with a projection or stop 12 to prevent the weighted end of the latch from dropping too far when the lid is raised, and to always insure the latch being 60 in the proper position to receive the projecting plate 6 when the tray is raised.

If the lid 2 and the tray 4 are in the raised position, with the hook end 10 of the latch 8 in engagement with the projecting plate 6 on the tray 4 and it is desired to close the trunk, it is not necessary to first disengage said latch 8 from said projecting plate 6 as this will be done automatically as the lid and the tray are lowered together.

70 The tray swings upon the point 5 as a center and the lid swings upon the point 3 as a center, causing the plate 6 on the tray to describe a different arc than that described by the point of the latch 8 thus causing the 75 plate 6 on the tray to slip off the hook of the latch 8, due to the action of the stop 12 in the lid which engages the latch and holds it so that the plate 6 may slip off the hook of said latch, which will release the tray as it descends into the trunk body. The latch 8 when released will assume the position shown in dotted lines Fig. 1, by the action of the 80 weighted end of the latch.

When the lid is raised the latch will be 85 held, by the stop 12, in a position to receive the plate 6 when the tray is raised. The edge of said plate 6 strikes the curved surface of the hook end of the latch which will move the hook end of the latch away from the stop 90 12 sufficiently to allow the hook to engage the plate 6 and the hook will then be held in engagement with the plate 6 by the action of the weight on the opposite end of the latch.

Having thus described my invention I 95 claim and desire to secure by Letters Patent:

1. In a trunk tray holder, the combination of a trunk body, a lid, a tray, hinged upon said trunk body in which said lid and said tray are eccentrically mounted, a projecting 100 plate on said tray, a latch pivoted in said lid, a hook on said latch adapted to engage said projecting plate when the tray is raised and a stop in said lid against which said latch takes as the lid descends and separates said projecting plate from said latch.

2. In a trunk tray holder, the combination of a trunk body, a lid, a tray, hinges upon said trunk body in which said lid and said tray are eccentrically mounted, a projecting 110 plate on said tray, a latch pivoted in said lid, a hook on said latch adapted to engage said

projecting plate when the tray is raised, a stop in said lid against which said latch takes as the lid descends and separates said projecting plate from said latch, said latch having its point curved to form a cam surface by which said projecting plate may move said latch and means for holding said latch in engagement with said projecting plate when said tray is raised.

- 10 3. In a trunk tray holder, the combination of a trunk body, a lid, a tray, hinged upon said trunk body in which said lid and said tray are eccentrically mounted, a projecting plate on said tray, a latch pivoted in said lid, a hook on said latch adapted to engage said projecting plate when the tray is raised, a stop in said lid against which said latch takes as the lid descends and separates said projecting plate from said latch, said latch having its point curved to form a cam surface by which said projecting plate may move said latch and a weighted portion on the end of said latch opposite to the end which engages said projecting plate.
- 15 4. In a trunk tray holder, the combination of a trunk body, a lid, a tray, a projection carried by said tray, a plate secured in said lid, a latch pivoted to said plate, a hook
- 20
- 25

formed on one end of said latch, a weighted portion of said latch opposite the end carrying the said hook and a projection on said plate to hold the said latch against the action of the weighted end of said latch when the lid is raised and to force said latch out of engagement with the projection on said tray when the lid is closed.

5. In a trunk tray holder, the combination of a trunk body, a lid, a tray, a projection carried by said tray, a plate secured in said lid, a latch pivoted to said plate, a hook 40 formed on one end of the said latch, a cam surface formed on said hook by which said projection on said tray may depress said hook, a weighted portion on said latch opposite the end carrying the said hook and a projection on said plate to hold the said latch against the action of the weighted end of said latch when the lid is raised and to force said latch out of engagement with the projection on said tray when the lid is closed.

In testimony whereof I affix my signature in presence of two witnesses.

OTTO RANGNOW.
